UNITED STATES PATENT OFFICE.

MILO M. SCHELL, OF WEST ALEXANDRIA, OHIO, ASSIGNOR OF ONE-HALF TO JOHN W. TRUMP, OF ARCANUM, OHIO.

FLEXIBLE GARMENT-FASTENER.

1,108,796.

Specification of Letters Patent. Patented Aug. 25, 1914.

Application filed March 25, 1914. Serial No. 827,229.

To all whom it may concern:

Be it known that I, MILO M. SCHELL, a citizen of the United States, residing at West Alexandria, in the county of Preble and State of Ohio, have invented certain new and useful Improvements in Flexible Garment-Fasteners, of which the following is a specification.

My invention relates to a "flexible garment fastener," which is intended for service on various articles of wearing apparel; such as men's shirts; women's waists; and in fact any and all kinds of garments that a flexible fastener is adapted for; but said fastener is more especially and particularly designed for shirts, under-shirts, waists, and all garments of the negligée class.

Some of the principal objects of this invention consist, in providing a ready and handy means for fastening or securing together the divided parts of a garment, and which is intended and adapted to take the place of the very objectionable buttons, also hooks and eyes which are constantly breaking or coming off the garment.

Another object is to provide a fastening or securing means for wearing apparel, that is soft and flexible and will not injure the garment when laundered;—thereby prolonging the life of said garment.

Further objects are to provide a fastener as above referred to, that is very efficient and durable; is quite simple in construction; and one that is inexpensive.

This invention consists essentially,—referring briefly and in general terms to my flexible fastener;—of the very peculiar arrangement and combination of the different parts; which will hereinafter be fully described in detail, and set forth in the subjoined claims all in accordance with the statutes in such cases made and provided therefor.

Referring to the accompanying drawings constituting a formal part of this specification and illustrating one form of construction for carrying out the objects and principles of my invention, and wherein the same letters are utilized to refer to, and indicate the same parts wherever occurring throughout the several views:—Figure 1 is a view in front elevation of a man's shirt equipped with my flexible fastener, —in operative position: —a portion of the sleeves and the body thereof being removed. Fig. 2 is a

cross sectional view through the collar of the shirt; the inclosing-tube or channel and the retaining cord;—as shown in Fig. 1. Fig. 3 is a sectional view through a portion of the front of the shirt on one side of the opening, showing two of the slotted openings or eyes with the retaining loops extending therethrough and the retaining-cord in position; and Fig. 4 is a view of a portion of the shirt front on the side of the opening or slit, having the end of the cord formed with the retaining loops, —two of said loops being shown.

In describing my said invention specifically and referring in detail to the different parts or elements, which combine to make up and complete my flexible garment fastener, as shown throughout the several views of the drawings and pointed out therein by means of the characters of reference as aforesaid: A refers to a garment embodying my invention, and which in this instance for the purpose of illustration, I have selected a man's shirt; on the side a,—see more particularly Figs. 1 and 4;—of the usual opening or slit in the front or bosom of said shirt, by which it is passed over the head when said shirt is placed in position on the wearer in the ordinary and well known manner; is securely attached or connected,—preferably by being sewed,—the end b of a retaining-cord or flexible member, which is formed at any desired and suitable distance apart, into loops c as shown: in this instance I have shown in the drawing three of said loops, but it is obvious that the number may vary according to the size of the shirt and to suit the ideas of the wearer. The loop coming at the neck of said shirt has the end forming the free end d of the retaining-cord or flexible member, passing through an inclosing tube or channel e—preferably made from the same material as the shirt,—said tube extending around the neck of the shirt under the collar f. The opposite side g,—see Figs. 1 and 3;—of said opening or slit in the front or bosom of the shirt heretofore referred to, and which overlaps side a, is provided with small slots or eyes h, each one of which registers in alignment with and extends at right angles to one of each of the loops c; i. e. there is a slot for each loop: each of said slots of course being worked around the edge in the usual manner similar to a button hole; and

through each of which—when the garment is in operative position or the position it is intended to assume when on the wearer as shown in Fig. 1,—extends one of the loops ⁶ *c*, and through each of said loops is passed the free end *d* of the retaining-cord after it has passed through tube *e*, as heretofore described: end *d* is then tied into a bow *k*—or if so desired into a loose knot and the end ¹⁰ then passed through said shirt opening, or in fact end *d* can be arranged in any suitable retaining manner desired. It will of course be readily understood that to remove said shirt from the wearer, it is only necessary ¹⁵ to untie said bow or knot, when free end *d* of said cord will readily be drawn upward through loops *c* and tube *e* sufficiently, as sides *a* and *g* are parted, to allow said shirt to be removed in the usual manner. If so ²⁰ desired said cord may be of a different shade or color from the garment: *i. e.* if the garment is of a dark color the cord may be of some light bright color, or vice versa:—if the garment is of a light color the cord ²⁵ might be of a dark color, thereby enhancing the appearance of the garment.

Having now described my flexible garment fastener,—in connection with the illus-

trations;—as my invention and as new; I claim—

1. A garment provided with a neck opening and a slit extending downwardly therefrom, and having slots formed in one of the sides of said slit, a flexible member secured to said garment and formed with loops ³⁰ adapted to pass through said slots, said member being slidably retained around the neck of said garment and having its free end passed through said loops; substantially as described.

2. A garment provided with a neck opening formed with a tube, and a slit extending downwardly therefrom, and having eyes located in one of the sides of said slit, a cord securely attached to said garment and formed with loops adapted to pass through said eyes while the free end of said cord passes through said tube and said loops; all substantially in the manner and for the purposes described.

In testimony whereof I affix my signature in presence of two witnesses.

MILO M. SCHELL.
